UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

LAMP.

1,382,903.

Specification of Letters Patent. Patented June 28, 1921.

Application filed March 15, 1920. Serial No. 365,766.

To all whom it may concern:

Be it known that I, CHARLES E. GODLEY, a citizen of the United States, and residing at Detroit, in the county of Wayne and State 5 of Michigan, have invented a new and Improved Lamp, of which the following is a specification.

This invention relates to means for positioning and for holding the reflectors of electric headlights and similar lamps from turning and consists in forming a radial flange on the reflector with a plurality of indentations which are adapted to receive an inwardly extending tongue on the body of the 15 lamp, one of the indentations registering with the tongue when the reflector is being moved into the lamp and the other to stop the reflector when it has been turned a predetermined distance and to prevent the reflector from turning back to removing position.

It also consists in mounting the locking tongue on a resilient leaf, preferably sheared from the body of the headlight, so that the 25 tongue may be swung out of engagement in said second notch.

It further consists in the details of construction illustrated in the accompanying drawing and particularly pointed out in the 30 claims.

In the drawings, Figure 1 is a front elevation of a lamp body and a reflector mounted therein. Fig. 2 is a section on the line 2—2 of Fig. 1. Fig. 3 is an elevation similar 35 to Fig. 1 with the reflector rotated within the lamp body to locked position. Figs. 4 and 5 are sections on the lines 4—4 and 5—5 of Fig. 3 respectively. Figs. 6 and 7 are front elevations of a lamp having a modified form of reflector lock. Fig. 8 is a side elevation of this lamp. Figs. 9, 10 and 11 are sections on the lines 9—9, 10—10 and 11—11 of Fig. 8 respectively.

Similar reference characters refer to like 45 parts throughout the several views.

The cup-shaped lamp body 1 shown in Figs. 1 to 5 inclusive is provided with an internal groove which results in an external circumferential bead 2, and it terminates in 50 the cylindrical ring 3. In this groove is mounted a circumferential wire spring 4 which has a number of V-shaped ears 5 which press against the radial flange 6 of the reflector 7 to force it outward. This flange 6 55 has a series of notches 8 through which pass

the retaining pins 9 by means of which the reflector is held in position.

Tongues 11 and 12 are struck up from this flange 6 of the reflector and project from the outer side of this flange and leave notches 14 and 15 in the edge thereof. A tongue 16 extends inwardly from the ring 3 of the body and is adapted to pass through these notches. The reflector may be formed with an opening 17 and the lamp body with a 60 lens 18, through which opening and lens the rays from the bulb 19 may pass.

When the reflector is to be mounted in the body it is turned until the pins 9 are in alinement with the notches 8 and the tongue 65 16 with the notch 15. The reflector is then pushed in until the flange 6 is back of the pins 9 and the tongue 16, when it is turned until the tongue 11 contacts with the tongue 16, as shown in Fig. 3. It is then released, 70 whereupon the ears 5 press the reflector outward until the flange 6 presses against the pins 9 at which time the tongue 16 enters the notch 14. This prevents the reflector from turning until the reflector is again 75 pushed back until its flange 6 is back of this tongue 16, when it can again be turned to the position shown in Fig. 1 and removed from the lamp body. The tongue 12 prevents the reflector from being turned too far 80 and serves to aline the notches 8 with the pins 9.

In the structure shown in Figs. 6 to 11 inclusive, slightly different details are advisable owing to the fact that there is no 85 spring within the body to press the reflector outward. The structure here shown is adapted to be used with a lens ring and locking ring such as shown in my prior Patent No. 1,340,163, dated May 18, 1920, but 90 this locking ring and lens ring form no part of the present invention.

The cup shaped body 21 of the lamp has a bead 23 and a circular end 22. The reflector 24 has a radial flange 25 provided 100 with notches 26 to permit the passage of the pins or tongues 27 extending inwardly from the end 22 of the lamp body. If desired, these tongues may be struck up from the metal of the body. A second set of tongues 105 28 also extend inwardly, and against them the flange 25 on the reflector is positioned. Thus far the structure is the same as that of my prior application.

In the edge of the flange 25 of the reflector 110

are two additional notches 29 and 30, the former having an inclined wall 32. The end 22 of the body is sheared along the line 33 (Fig. 8) to produce a resilient keeper 34 having an inturned lip 35 which is of such a length longitudinally of the axis of the lamp that the flange 25 can never be moved below it.

When the lamp is to be assembled, the reflector is positioned in the body, as shown in Fig. 6, with the pins 27 passed through the notches 26 and the flange 25 on the reflector against the tongues 28. The reflector is then turned to the left to the position shown in Fig. 7, the tongue 35 on the keeper 34 riding up on the inclined wall 32 of the notch 29, and moving into the notch 30 when that is reached. The tongues 27 prevent the reflector from moving out and the tongue 35 prevents it from turning until this keeper is sprung out far enough to move the tongue 35 out of the notch 30 which is readily done by pressing outwardly with any small flat object on the inner end of this tongue while the reflector is being turned sufficiently to carry the notch 30 out of alinement with the tongue. Thereafter the reflector may be turned to normal position.

In each embodiment the lamp body is formed with retaining pins or fingers to prevent the outward movement of the reflector and the reflector is provided with notches to permit these retainers to pass. The reflector is also formed with two notches which may be entered by a stop on the body, one of the notches serving as a passage for the stop when the reflector is placed within the body and the other notch being adapted to receive the stop and thus limit and prevent the movement of the reflector.

The sizes and proportions of the various details may all be modified by skilled lamp makers without departing from the spirit of my invention as set forth in the following claims.

I claim:—

1. In a lamp, the combination of a cup-shaped body having a cylindrical open end, retaining devices extending inwardly from said cylindrical end, a reflector movable into said body and having a radial flange adapted to slide within the cylindrical end of said body, said flange being formed with notches adapted to permit said retainers on the body to pass through, said flange being also formed with two additional notches, and a resiliently mounted outwardly movable tongue extending inwardly from said cylindrical end of the body and adapted to enter said additional notches.

2. In a lamp, the combination of a cup-shaped body having a cylindrical open end, retaining devices extending inwardly from said cylindrical end, a reflector movable into said body and having a radial flange adapt-

ed to slide within the cylindrical end of said body, said flange being formed with notches adapted to permit said retainers on the body to pass through, said flange being also formed with two additional notches, a tongue extending inwardly from said cylindrical end of the body and adapted to enter said additional notches, and a resilient support for said tongue mounted on said cylindrical end of the body and adapted to be swung out beyond the circumference of said flange in the reflector to carry the tongue out of said notches.

3. In a lamp, the combination of a cup-shaped body having a cylindrical open end, retaining devices extending inwardly from said cylindrical end, a reflector movable into said body and having a radial flange adapted to slide within the cylindrical end of said body, said flange being formed with notches adapted to permit said retainers on the body to pass through, said flange being also formed with two additional notches, a tongue extending inwardly from said cylindrical end of the body and adapted to enter said additional notches, the wall of one of the additional notches in said flange being inclined, and a resilient support for the tongue which may be forced out of said notch by said inclined wall when the reflector is turned.

4. In a lamp, the combination of a cup-shaped body having a cylindrical open end, a tongue extending inwardly from said open end, a reflector for said lamp having a radial flange provided with two notches which may be entered by the tongue, said reflector being inserted into the body in such position that the tongue is in alinement with the first notch, after which the reflector may be turned until the tongue is in alinement with the second notch, and retaining means to prevent the removal of the reflector after the first notch has been moved out of alinement with said tongue, the flange on the reflector being in the same radial plane as the tongue when the reflector is held in position by said retaining means.

5. In a lamp, the combination of a body having a cylindrical open end, rigid members extending inwardly from the open end, a reflector rotatably mounted in said open end and having a radial flange provided with notches in its edge to pass said projections, and a resiliently mounted member adapted to engage in a notch in said flange of the reflector to prevent it from turning.

6. In a lamp, the combination of a body having a cylindrical flange and projections on the inner side of said flange, and a reflector having a radial flange provided with notches to pass the projections, said cylindrical flange being circumferentially slotted to form a resilient keeper having an in-turned lip and the radial flange on the re-

flector having notches to receive the lip and thus limit the rotation of the reflector.

7. In a lamp, the combination of a body having a cylindrical flange and projections 5 on the inner side of said flange, and a reflector having a radial flange provided with notches to pass the projections, said cylindrical flange being circumferentially slotted to form a resilient keeper having an in- 10 turned lip and the radial flange on the reflector having notches to receive the lip and thus limit the rotation of the reflector, said radial flange having its edge formed with an inclined portion extending to the bot-

tom of one notch so the lip may ride on said 15 edge to the adjacent notch.

8. In a lamp, the combination of a body having an open end, a reflector rotatably mounted in said open end and having a radial flange provided with a notch, means 20 to hold the reflector in the lamp body, and a resilient member mounted on said open end of the body and movable substantially radially and adapted to enter the notch in the flange to prevent the reflector from rotating 25 in said body.

CHARLES E. GODLEY.
